(57) **CLAIM**

The ornamental design for a display screen or portion thereof with graphical user interface as shown and described.

DESCRIPTION

FIG. 1 depicts a front view of a display screen or portion thereof with graphical user interface showing a first embodiment of the claimed design.

FIG. 2 depicts a front view of a display screen or portion thereof with graphical user interface showing a second embodiment of the claimed design.

FIG. 3 depicts a front view of a display screen or portion thereof with graphical user interface showing a third embodiment of the claimed design.

FIG. 4 depicts a front view of a display screen or portion thereof with graphical user interface showing a fourth embodiment of the claimed design.

FIG. 5 depicts a front view of a display screen or portion thereof with graphical user interface showing a fifth embodiment of the claimed design; and,

FIG. 6 depicts a front view of a display screen or portion thereof with graphical user interface showing a sixth embodiment of the claimed design.

The outermost broken line in each figure shows a display screen or portion thereof and forms no part of the claimed design.

The dash lines inside the outermost broken line depict portions of the graphical user interface forming no part of the claimed design.

(Continued)

The dot-dash lines inside the outermost broken line depict boundaries of the claimed design and form no part thereof.

1 Claim, 6 Drawing Sheets
